SLIT RUBBER NIB FOR GARMENT HANGERS

Dorothy Jacob, Brooklyn, N. Y., assignor of
ninety-nine per cent to Helen Unterman,
Brooklyn, N. Y.

Application January 3, 1952, Serial No. 264,702

3 Claims. (Cl. 223—92)

1

My present invention relates to slit rubber nibs for garment hangers and to a garment hanger provided adjacent its ends with such rubber nibs for the purpose of retaining on the hanger dresses, gowns and the like having relatively low necklines and sleeveless evening gowns and garments having halter and strap tops.

Difficulty is encountered in connection with existing garment hangers for low-neck dresses and gowns, sleeveless evening gowns and other garments such as those having halter and strap tops in that they either slip off the hangers or become damaged thereby, due to the existing custom of providing modern hangers with cut-out portions and projections. In many such instances, particularly where lace and soft fabrics are involved, portions of the hangers pierce or tear or otherwise rub or damage the material and such garments also readily slide or fall off the hangers.

It is an object of the present invention to provide a hanger having rubber nibs which overcomes the defects and disadvantages of existing hangers and which has new and useful advantages not heretofore attained in hanger construction.

Another object of the invention resides in providing existing types of hangers with a special slitted rubber nib near each end thereof which not only serves to prevent the garments from accidentally coming off the hangers but which have protective features obviating damage to the garments.

A still further object of the invention resides in the construction of the rubber nibs and the manner of use thereof, such nibs being adapted to be applied to existing hangers of various types and constructions as will hereinafter be explained.

Other and still further objects and advantages will be understood and appreciated by those skilled in the art or will be apparent or pointed out below.

In the accompanying drawing:

Fig. 1 is an end elevational view of a slitted rubber nib embodying my present invention;

Fig. 2 is a side elevational view of the rubber nib of Fig. 1;

Fig. 3 is a vertical sectional view of the rubber nib taken along line 3—3 of Fig. 2;

Fig. 4 is a perspective view of the rubber nib of Figs. 1-3;

Fig. 5 is a front elevational view of a garment hanger provided with a pair of rubber nibs according to the invention and showing the rela-

2

tionship therewith of a low-necked gown or other garment provided with sleeves;

Fig. 6 is a view similar to Fig. 5 but showing the manner of using the invention for a sleeveless gown or garment, and

Fig. 7 is a front elevational view of a conventional type of wooden hanger showing how the rubber nibs are associated therewith.

Referring now to the drawings in detail, and first to Figs. 1-4, thereof, the numeral 10 indicates a rubber nib having suitable resiliency and elasticity and having a hollow, oval-shaped body portion defining the elongated oval opening 11. Such a nib is preferably of molded rubber but may be extruded, if desired. At its upper end, the nib has a relatively thick upwardly tapering extension 14 terminating in a rounded point or apex 13. Formed in the tapering extension 14 and at or just slightly above the junction thereof with the oval body of the nib is a slit or cut 12 which, as will be more clearly apparent from Fig. 2 or 4, extends from one edge of the nib but terminates short of the opposite edge, so that the extent of the slit or cut is a major protuberance of the width of the nib but is substantially shorter than the nib, thus providing an uncut or unslotted portion 15 between the terminus of the cut or slit and the opposite edge of the nib. Thus, a relatively strong construction is produced which has a long life and is durable for many successive uses, it being understood that the cut or slit is opened somewhat by upward pressure above the cut or slit for the insertion or removal of garments and that it thereafter reverts back to its former condition and exerts an adequate frictional grip upon the material of the garment, the uncut portion serving as a body about which the cut portion can be bent. The body portion of the nib is relatively thin, flexible and elastic so that it can conform to the various sizes and shapes of hangers, whether they are flat or rounded, and the nature of the nib material permits deliberate movement of the nib along the hanger to adjust or vary their spacing but adequately resists undesired slippage. While the slit or cut 12 has an adequate frictional grip as shown, the bounding surfaces thereof may be roughened, if desired, for increasing their gripping power.

The nib above-described is adapted to be used in different manners depending upon the type of garment which is to be held in place on the hanger. In Fig. 5 I have illustrated the use of my new rubber nibs on a hanger construction which may be of any suitable or known config-

ation such as a flat transparent plastic hanger designated by the numeral 16 with its conventional hook 17. Such a hanger usually is provided with elongated cutouts 18 having spaced projections 19 which have heretofore been employed for engagement with the garment and such hangers are customarily also provided with a spirally cut-out portion 20 at the underside of each arm of the hanger. It is these portions of the hanger which are particularly apt to damage garments. A rubber nib 10 is shown as having been applied to each arm of the hanger 16 and these are positioned for a particular garment depending upon the neckline of such garment, and it is understood that the nibs may be moved inwardly or outwardly along the hanger arms so as to change the positions thereof and more particularly, the spacing therebetween to accommodate garments having different sizes of neckline. It will be particularly noted in Fig. 5 that the nibs are so applied to the hanger that the slits 12 thereof face outwardly. The concave line 21 indicates the top edge of the neckline of a garment and shows how the opposite edges of the material at the neckline are engaged within the slits 12 and are held thereby with a frictional grip sufficient to prevent the garment from falling off the hanger or even from being dislodged therefrom by rough handling or shaking of the hanger. Such a garment is usually provided with sleeves, indicated at 22, showing how these are located with respect to the remainder of the hanger and the nibs.

In Fig. 6 an evening gown 23, or the like, is shown which may, however, be any garment which is sleeveless and it will be noted particularly that, in the case of sleeveless garments or garments the upper portion of which is merely in the form of straps such as in bathing suits, halter-type garments, etc., the nibs 10 are so positioned on the arms of the hanger 24, having the usual hook 25, that the slits 12 thereof face inwardly toward the center of the hanger and not outwardly away from the center of the hanger, as is the case in Fig. 5. In Fig. 6 the sleeveless garment 23 has edge portions thereof frictionally gripped within the slits 12 and, as has been explained ament Fig. 5, the positions of the nibs 10 on the hanger arms may be intentionally varied by moving the same inwardly or outwardly so as to accommodate the spacing between the nibs to the particular garment and its design, wherever necessary. In such case, also, it will be noted that there is exceptional resistance against the garment's sliding off the hanger or of being inadvertently dislodged therefrom.

By comparing Figs. 5 and 6, it will be appreciated that my invention is adaptable to all types of garments which are customarily placed on hangers in a show-room, salesroom, closet, wardrobe, or the like, and that by the use of the invention such garments do not have any tendency to slide off the hangers and resist even rough handling; furthermore, the garments are not subject to being damaged by the hangers themselves, this being an especially troublesome problem in connection with lace or net garments or garments having lace or other trimming around the neckline. Fig. 6 further illustrates another form of conventional hanger having reverse projections 26 which are especially apt to pierce or damage garments and it will be noted that the positions of the nibs are such that the garment is not in contact with the points of such projections.

In Fig. 7 a conventional wooden hanger 27 is

illustrated which may either be flat or round in cross-section and to which my rubber nibs 10 have been applied, as shown, with the slits 12 thereof directed outwardly, it being understood that, if such a hanger is intended for use with sleeveless garments, the nibs are reversed so that the slits 12 face inwardly as in Fig. 6.

From the foregoing it will be apparent that in a simple, inexpensive and highly effective manner I have made it possible to convert garment hangers of various types into hangers especially adapted for protecting garments while preventing their inadvertent removal therefrom. Depending upon whether the garment has sleeves or is sleeveless, the nibs are assembled and placed upon the hanger with the slits thereof facing outwardly or inwardly, respectively. The nibs tightly grip the hangers but can be intentionally moved therealong and thus can be positioned close to the ends of the arms of the hangers to accommodate garments of the larger sizes. The slits provide strong frictional grips on the garments without unduly interfering with removal of the garments from the hangers.

The slits 12 may be formed in the rubber nibs at any suitable stage in their production. When molded rubber nibs are produced, molding being the preferred procedure, the slits can be formed during molding by suitable knives or slitters or the slits may be subsequently formed after the nibs are removed from the molds. The slits are preferably located at the juncture of the portions 10 and 14 where the material of the nibs is the thickest, as clearly shown in the drawing, and such slits are very small being of the order of $\frac{1}{32}$ " and the resiliency of the rubber normally maintains the slits in substantially closed position as will be noted. The nibs shown in Figs. 1-4 are approximately actual size.

In applying a sleeved garment to the hanger of Fig. 5, one end of the hanger is inserted into the garment through the neckline opening and the opposite side of the neckline of the garment is positioned in the slit of the nib, as shown at the right of Fig. 5; then the inserted hanger end is brought up to the position shown at the left of Fig. 5 and the adjacent portion of the garment at the neckline is inserted in the slit of the opposite nib. To insert the garment in the slit, the upper portion of the nib is slightly raised to open the slit just enough to permit insertion of the garment edge and then the upward pressure is removed to allow the slit to clamp upon the garment material. To remove the garment, the reverse procedure is followed. Analogous procedure is followed in the case of Fig. 6 as will be clearly apparent from the foregoing.

From the foregoing it will be understood that various advantages are derived from the application of my new nibs to standard forms of hangers and that these advantages cannot be obtained from hangers lacking such rubber nibs. It will further be understood that the foregoing is intended as illustrative and not as limitative since, within the terms of the appended claims, other variations and modifications may be made without departing from the invention.

I claim:

1. A nib adapted to be applied to a garment hanger having a pair of oppositely extending, angularly disposed arms and comprising a hollow, oval-shaped thin, resilient and elastic body portion adapted to fit over and accommodate itself to such garment hanger arms and provided with a relatively thick, upwardly tapering top portion having a rounded apex, the relatively thick

top portion being provided adjacent its juncture with the body portion with a slit extending from one edge thereof toward but terminating short of the opposite edge, said slit being adapted to receive and frictionally hold a garment therein.

2. A nib for garment hangers in accordance with claim 1 in which the nib is composed of rubber and in which the body portion is substantially equal in size to a cross-section of said hanger arms.

3. A nib for garment hangers in accordance with claim 2 in which the said slit is substantially parallel to the upper edges of said hanger arms.
